CLAIM

The ornamental design for a tensioning tool, as shown and described.

DESCRIPTION

FIG. 1 is a top, front, and right side perspective view of the tensioning tool showing the new design;

FIG. 2 is a top, front, and left side perspective view of the tensioning tool showing the new design;

FIG. 3 is a front view of the tensioning tool showing the new design;

FIG. 4 is a rear view of the tensioning tool showing the new design;

FIG. 5 is a top view of the tensioning tool showing the new design;

FIG. 6 is a bottom view of the tensioning tool showing the new design;

FIG. 7 is a left side view of the tensioning tool showing the new design;

FIG. 8 is a right side view of the tensioning tool showing the new design;

FIG. 9 is a bottom, rear, and right side perspective view of the tensioning tool showing the new design; and,

FIG. 10 is a top, rear, and right side perspective view of the tensioning tool showing the new design. The dotted lines shown in FIG. 10 represent human thumbs and a rope and are included for the purpose of illustrating the manner in which the tensioning tool showing the new design can be used and form no part of the claimed design.
